UNITED STATES PATENT OFFICE.

FRANCIS A. BATES, OF PHILADELPHIA, PENNSYLVANIA, ASSIGNOR TO THE MORSE, WILLIAMS & COMPANY, OF PENNSYLVANIA.

DESIGN FOR A CROSS-HEAD FOR HOISTING MACHINERY.

SPECIFICATION forming part of Design No. 25,778, dated July 14, 1896.

Application filed May 23, 1896. Serial No. 592,881. Term of patent 7 years.

To all whom it may concern:

Be it known that I, FRANCIS A. BATES, of the city and county of Philadelphia, State of Pennsylvania, have invented and produced 5 a new and original Design for Cross-Heads of Hoisting Machinery, of which the following is a specification.

My design is illustrated in the accompanying drawings, in which—
10 Figure 1 is a plan view of the cross-head with part in horizontal section, and Fig. 2 is a side elevation of the same.

The cross-head consists of a U-shaped frame, as shown, having the two projecting 15 arms A A and the rear transverse body B, with the socket C. The arms A A have boxes

or hollow parts D D at their rear portions, at which are located tubular bosses E E. The boxes or hollow parts D D are open at the bottom. The front ends of the arms have 20 cup-shaped recesses F F.

What I claim as new, and desire to secure by Letters Patent, is—

The design for cross-heads for hoisting machinery substantially as shown and described. 25 In testimony of which invention I have hereunto set my hand.

F. A. BATES.
